(57) **CLAIM**

The ornamental design for a curling iron, as shown and described.

DESCRIPTION

FIG. 1 is a top, right side perspective view of a new, original and ornamental design for a curling iron according to one embodiment;

FIG. 2 is a top plan view of FIG. 1;

FIG. 3 is a bottom plan view of FIG. 1;

FIG. 4 is a left side elevation view of FIG. 1;

FIG. 5 is a right side elevation view of FIG. 1;

FIG. 6 is a rear elevation of FIG. 1;

FIG. 7 is a front elevation view of FIG. 1;

FIG. 8 is a bottom, right side perspective view of FIG. 1;

FIG. 9 is a bottom, left side perspective view of FIG. 1;

FIG. 10 is a top, right side perspective view of a new, original and ornamental design for a curling iron according to another embodiment;

FIG. 11 is a top plan view of FIG. 10;

FIG. 12 is a bottom plan view of FIG. 10;

FIG. 13 is a left side elevation view of FIG. 10;

FIG. 14 is a right side elevation view of FIG. 10;

FIG. 15 is a rear elevation of FIG. 10; and,

FIG. 16 is a front elevation view of FIG. 10.

The broken lines in the drawings depict portions of the curling iron that form no part of the claimed design.
